UNITED STATES PATENT OFFICE.

WILLIAM H. THOMPSON, OF PHILADELPHIA, PENNSYLVANIA, ASSIGNOR
OF ONE-HALF TO WILLIAM W. DRYDEN, OF PHILADELPHIA, PENN-
SYLVANIA.

BULB-MANIPULATOR.

SPECIFICATION forming part of Letters Patent No. 787,805, dated April 18, 1905.

Application filed June 25, 1904. Serial No. 214,091.

To all whom it may concern:

Be it known that I, WILLIAM H. THOMPSON, a citizen of the United States, residing at the city of Philadelphia, in the county 5 of Philadelphia and State of Pennsylvania, have invented certain new and useful Improvements in Globe-Manipulating Devices, of which the following is a specification.

My invention has relation to a device for 10 permitting of quickly inserting and removing incandescent-electric-light bulbs into and from their sockets, and in such connection it relates to the particular construction and arrangement of such a device for the said purposes.

The nature and scope of my invention will 15 be more fully understood from the following description, taken in connection with the accompanying drawings, forming part hereof, in which—

Figure 1 is an elevational view of a device 20 of my invention embodying main features thereof and a broken section of the pole therefor. Fig. 2 is a side elevational view of the device, showing the angular position that the gripping-fingers of the device may be 25 caused to assume in certain instances for either inserting a bulb into or removing the same from its socket; and Fig. 3 is a vertical 30 sectional view of the device, in broken section, showing detail construction and arrangement of main operative features thereof.

Referring to the drawings, *a* is a pole or 35 rod for the globe or bulb manipulating device, provided with an adjustable tightening device *b*, having a locking-pawl *b'*, provided with a groove *b²* and a tongue *b³*, adapted to traverse the slot *b⁴* of this tightening device.

d is a yoke-frame pivotally clamped, as 40 shown, by means of a tightening-nut *h*, to the pole or rod *a*. The yoke-frame *d* is provided with a central transverse opening or seat *d²* for a grooved pulley-wheel *e* and with an end opening *d⁵* at right angles to the 45 pulley-seat to form a bearing for a shaft *c²*, carrying a series of gripping-fingers *c'*, mounted in said bearing. The pulley-wheel

e is tightened or loosened on the shaft *c²* by means of a set-screw *d⁴*. Through the yoke-frame *d* is inserted a set-screw *g* for clamping the shaft *c²* from the said frame.

Between the adjustable tightening device *b* of the pole or rod *a* and the grooved pulley-wheel *e* is an endless-cord connection *f* for permitting of the actuation of the pulley as required.

When the set-screw *g* is brought into firm engagement with the shaft *c²*, there is prevented the turning of the shaft by the pulley-wheel *e* when the yoke-frame and pole occupy the position as illustrated in Fig. 1, for the reason that in such position inserting or removing of a bulb or globe from its socket is effected simply by turning or revolving by hand the pole or rod *a* with the gripping-fingers in engagement with the bulb or globe, while, on the other hand, when the yoke-frame *d*, with its shaft *c* and gripping-fingers *c'*, has been caused to assume the position shown in Fig. 2, with the cord *f* taut between the pulley-wheel *e* and the adjustable tightening device *b*, by drawing on the cord the pulley-wheel *e* can be readily revolved and therewith the gripping-fingers *c'* rotated with a bulb or globe between them for either inserting the bulb in its socket or for removing the same therefrom. In this instance it will be understood that the set-screw *g* will be brought out of engagement with the shaft *c²*, so as to permit of the free rotation thereof in the yoke-frame *d*.

Having thus described the nature of my invention, what I claim as and desire to secure by Letters Patent,

In a globe-manipulating device, the combination with a pole or rod, a yoke-frame pivotally clamped to said rod, said yoke-frame having a central transverse opening or seat for a pulley-wheel, and an end opening at right angles to the pulley-seat forming a bearing for a shaft carrying gripping-fingers mounted in said bearing, a grooved pulley-wheel, and means for clamping the pulley-wheel to its shaft and thereby

wenting removal of the shaft from said yoke-frame, of an adjustable tightening device on the rod and an endless-cord connection between said pulley-wheel and tightening device, substantially as and for the purposes described.

In testimony whereof I have hereunto set

my signature in the presence of two subscribing witnesses.

WM. H. THOMPSON.
